ELECTROLYTIC CONDENSER

Willem Christiaan van Geel and Hendrik Emmens, Eindhoven, Netherlands, assignors to Radio Corporation of America, a corporation of Delaware

Application February 25, 1932, Serial No. 594,982
In the Netherlands June 20, 1931

5 Claims. (Cl. 175—315)

This invention relates to improvements in electric condensers.

It is an object of this invention to simplify and improve the construction of electrolytic condensers so that the life of the condenser is increased.

In the customary construction of electrolytic condensers one electrode of such a condenser consists of a metal plate or a metal wire coated by electrolytic or chemical agency with an oxide 10 coating and immersed in an electrolyte constituting the other electrode. For this purpose the electrolyte is furnished with a conductor for the supply of the electric current, said conductor being formed, for example, by the wall of the vessel 15 in which the electrolyte is enclosed.

One of the difficulties which have to be overcome with such condensers is the attack of the oxide coating so that the life of the condenser is limited.

20 Now it has been found that this attack is to be imputed to a large extent to impurities enclosed in the electrolyte. Even when during the manufacture of the condenser a careful watch is kept that no impurities occur in the electrolyte, it is found that in the course of time they nevertheless occur. Indeed, they are absorbed 25 from the wall of the vessel or are due to the insulating parts which are used for taking the conductors through the wall of the vessel, said insulators containing in general organic material.

Even when use is made of electrolytes consisting of solutions of solid substances in alcohol, such as glycerol, which electrolytes otherwise have favourable properties with regard to leakage current and capacity, it is found that said disadvantage is not disposed of without additional means.

35 This has only been found possible by using a solution of one or more of the primary or secondary phosphates in an alcohol, for example of primary potassium phosphate in glycerol. This combination has been found to permit of the oxide coating of the metal electrodes being protected from attack.

40 Perhaps this striking action is to be imputed to the circumstance that it is found possible to dissolve a great deal of the solid substance primary potassium phosphate in the glycerol so that consequently the proportion of the quantity of 45 impurity in the liquid becomes negligible relative-

ly to the quantity of the substance dissolved in addition and also the influence of the impurities decreases thereby accordingly. In this case the circumstance that in spite of the large quantity of primary potassium phosphate which is dissolved the conductivity does not become great plays an important part since in most dissolved substances in which the quantity of the substance dissolved is comparatively large the conductivity of the electrolyte becomes great as well and incidental thereto is an inadmissible leakage current. However, this phenomenon does not occur in the said use of primary potassium phosphate.

5 Favourable results were obtained with a condenser one electrode of which was of aluminium, whereas the electrolyte consisted of pure glycerol having added to it 50 grams of primary potassium phosphate (KH_2PO_4) per liter.

Similarly, good results were obtained when this electrolyte had added to it in addition 10% of water.

25 When, for example, a solution of primary potassium or sodium phosphate is used, this solution is acid. Now, a further protection of the electrodes from attack can be obtained by adding to the solution a basicly reacting phosphate, for example secondary potassium or sodium phosphate, in such a proportion that the solution is just neutral.

In order that the invention may be clearly understood and readily carried into effect a condenser in accordance therewith will now be described more fully with reference to the accompanying drawing.

30 Referring to the drawing, a copper vessel 1 contains an electrolyte 2 consisting of pure glycerol in which primary potassium phosphate is dissolved in a proportion of 50 grams per liter of glycerol. On its upper side the vessel is closed by an ebonite disc 3 through which the end of an aluminium wire 4 is taken. In order to obtain a large surface area, the aluminium wire is wound helically. A plurality of such helices might be arranged one within the other. Leading-in wires may be connected to 5 and 6. The aluminium 35 wire is coated by chemical or electrolytic agency with an oxide coating which constitutes the insulating intermediate layer between the electrodes of the condenser.

45 A condenser as illustrated in the drawing is 50

- only suitable for smoothing direct current as it disrupts the current only in one direction. It can therefore be used as a rectifier as well. If such condensers are desired to be used for alternating current, a second aluminium electrode similarly coated with an oxide coating may be arranged in the electrolyte and the two aluminium electrodes may be connected to the terminals of the alternating current supply.
- 10 Various modifications are otherwise possible without departing from the scope of the invention. Thus, for example, the aluminium wire may be profiled in order to increase the surface area and instead of wire use may be made of 15 rolled-up plates the windings of which are kept apart by distance holders. Alternatively, the electrolyte may have added to it over 10% of water. Even with 30% of water good results have still been obtained.
- 15 20 We claim:
1. An electrolytic condenser comprising a metallic electrode, an oxide coating on said metallic electrode, an electrolyte consisting of a solution of acid phosphate, and alcohol of the 25 group including glycerol, for the purpose of preventing an attack on said oxide coating.
  2. An electrolytic condenser comprising a metallic electrode, an oxide coating on said

metallic electrode, and an electrolyte having the properties of preventing an attack on the oxide coating of said electrode, consisting of a solution of primary potassium phosphate in glycerol to which solution is added substantially 10% of 5 water.

3. An electrolytic condenser comprising a metallic electrode of aluminum having an oxide coating, and an electrolyte consisting of a solution of pure glycerol in which primary potassium phosphate is dissolved in a quantity of 50 grams per liter. 10

4. An electrolytic condenser comprising a copper vessel containing an electrolyte of pure glycerol in which primary potassium phosphate 15 is dissolved, an insulating disc enclosing said vessel, and an electrode of aluminum wire having an oxide coating which constitutes an insulating layer between the condenser electrode. 15

5. An electrolytic rectifier comprising a copper 20 vessel containing an electrolyte of pure glycerol in which primary potassium phosphate is dissolved, an insulating disc enclosing said vessel, and two electrodes of aluminum wire having an oxide coating which constitutes an insulating 25 layer between the rectifier electrodes.
